UNITED STATES PATENT OFFICE.

PALMER COX, OF NEW YORK, N. Y.

DESIGN FOR A RULER.

SPECIFICATION forming part of Design No. 22,583, dated July 4, 1893.

Application filed May 10, 1893. Serial No. 473,730. Term of patent 14 years.

To all whom it may concern:

Be it known that I, PALMER COX, a citizen of the United States, residing in the city, county, and State of New York, have invented a new and original Design for Rulers, of which the following is a specification, reference being had to the accompanying drawing, forming part thereof.

The design consists in four series of brownies each of which series may be termed as follows:—"Peeping brownies," "Peeping brownies on the fence," "Peeping brownies at rear window," "Peeping brownies at front window." They appear on the surface of a ruler as hereinafter described.

In the drawing:—the figure is a front surface of a ruler on which is shown my design.

The first series, namely, the "Peeping brownies," is composed of the original, dude, original, ordinary, royal, original, ordinary, Italian, original, Scotch, Indian, original, student, Turk, soldier, ordinary, Irish, Uncle Sam, ordinary, Russian, Scotch, Chinese, principal and original brownies.

The second series, namely, the "Peeping brownies on the fence," is composed of the Hollander, ordinary, Russian, jockey, soldier, Alpine, principal, Uncle Sam, Chinese, Sailor, Turk, twin, Scotch, policeman, ordinary, dude, original, Egyptian, student, Es-

quimau, Japanese, Alpine and ordinary Brownies.

The third series, namely, the "Peeping brownies at rear window," is composed of the original, ordinary, twin, Indian, English, Egyptian, student, Italian, ordinary, royal, Spanish, ordinary, Esquimau, French, original, Japanese, ordinary, ordinary, Highland, original, ordinary, Scotch and ordinary Brownies.

The fourth series, namely, the "Peeping brownies at front window," is composed of the ordinary, sailor, ordinary, Esquimau, Hollander, jockey, ordinary, Turk, Irish, soldier, principal, Arab, Chinese, Scotch, Uncle Sam, Canadian, German, ordinary, Alpine, Russian, original, ordinary and dude brownies.

The series of brownie characters is intended to give a pleasing effect to a ruler as well as to serve as an incentive to the use of rulers by children.

I claim—

The design for a ruler, substantially as herein shown and described.

PALMER COX.
